J. V. A. Wemple,

Horse Power.

Patented Mar 25, 1834.

Jacob V. A. Wemple, of Florida, N. York.
Letters Patent

The schedule referred to in these Letters Patent, and making part of the same, containing a description in the words of the said Jacob V. A. Wemple himself of his improvement in the machine for threshing grain & also in the construction & formation of a horse power for propelling said machine.

To all to whom these presents shall come: Be it known that I Jacob V. A. Wemple of the town of Florida in the ___ of Montgomery State of New York have invented a new & useful improvement in a machine for threshing grain - and the horse power operating said machine which horse power may be applied to all other uses & purposes to which horse power usually is or may be applied - and that the following is a full description of the construction & operation of said machine horse power as invented or improved by me - The machine is constructed with a frame four feet long two feet ten inches wide & two feet two inches high made with four posts three inches thick & six inches wide two plates three inches thick three inches wide two & three inches square - three girts or cross timbers three inches square at circular or concave bed two feet & four inches long which is to be made of hard wood plank eight inches wide & three & a half inches thick faced with sheet iron & tenoned into the plates or may be set on spiral springs & a cylinder of solid hard wood two feet three & a half inches long & nine inches in diameter or larger if thought proper bound with sheet iron, with an iron shaft running thro' the center of it an inch & a quarter square with a bed ring at each end of the cylinder; the end of the shaft projecting far enough to receive or whin of about five inches diameter - The ends of the cylinder are secured with iron bands - The cylinder is to run in cast iron boxes counter sunk in the center about three fourths of an inch & filled up with zinc for the bed rings - The boxes are in two pieces confined to th. plates by means of iron bolts - In the upper half of the box is a reservoir with a small hole thro' from the bottom of it to the shaft to contain oil for oiling the bearings - The teeth in the concave are an inch & a half long to the first shoulder, one inch wide at the shoulder & half an inch at the end three eighths of an inch thick at the shoulder & one fourth of an inch at the end of the edge opposite the shoulder being the part which strike the grain should be rounded to prevent its cutting the grain - The back of the teeth is four inches in length, two inches of which is only one fourth of an

each square with a flat point & is the part that is driven thro the concave & clenches on the under side. The teeth in the cylinder are the same as those in the concave except the neck which is three inches long, three quarters of an inch wide & three eights of an inch thick. The distance from center to center between the teeth in both the concave & cylinder is one inch & they are placed in such a manner that the teeth of the cylinder pass thro between those of the concave leaving a space between the teeth as the cylinder revolves of an eighth of an inch. In the cylinder are twenty five teeth set in rows, running half way around it in a spiral form & placed in such a manner as to break joint.

In the concave there are fifty two teeth set in four rows running lengthways of said concave also set in such a manner as to break joint. The cylinder is covered with a wooden cap into the ends of which is grooved diagonally a strip of a board about three & a half inches wide which forms a fender that prevents the dust from driving back up the throat of the hopper. This fender with an opening left in the cap next to the hopper forms the dust discharger. On the frame of the machine there is constructed a hopper or feeding table with a throat to receive the grain, one side of the hopper is seventeen inches high in order to prevent the grain from catching on the strap or band; the other side is only seven inches high. The improvement which I claim in the above threshing machine as my invention is the formation of the teeth & the construction of the dust discharger, also the lining of the boxes with zinc. The description of the horse power above mentioned is as follows. - The frame is made by tenoning two sills thirteen feet long, & six inches square into a cross sill six feet long, six inches thick & ten inches wide.

The long sills are seventeen inches apart where they are tenoned into the six feet sill & the other end they are twenty two inches apart. On the six feet sill near each end is a post thirteen inches long double tenoned which passes in a cap piece six feet long ten inches wide & five inches thick & in said cap piece & directly over the long sills are framed two plates four feet long & four by five inches square supported at the other end by two posts thirteen inches long framed into the long sills. There is a brace from the plate to the cap piece & also from this same plate an iron brace to the long sill on the opposite side secured by bolts. said frame contains the following gearing, one cast iron crown wheel three feet in diameter with spur gearing four inches wide to a cast iron shaft four inches square & twenty six inches long having perpendicular which said shaft steps into a box in the center of the six feet sill three & a half inches deep thro the cap piece which is confined by two half boxes with keys; on the top of this neck is a head fourteen inches long for

inch high & three inches across in the center tapering to an inch at the ends & in each end of the head is a notch to receive a bolt for securing on it a lever which is let on by means of a mortise in the center - The lever is twenty feet long eight inches square in the center tapering to three inches at the ends - The said crown wheel meshes into a seven inch pinion on another upright shaft of wrought iron seventeen inches long & two inches square which shaft steps into a box let into a cross sill tenoned into the long sills, turns at the top into a box bolted on a cross girt which is tenoned into the two plates -

The shaft of the pinion wheel is regulated by keys to the cross girt & sill so as to mesh in front with the crown wheel as may be necessary - On the shaft of the pinion wheel is also a band wheel of cast iron two feet in diameter which meshes into a six inch pinion wheel on a wooden shaft five inches in diameter nine feet long lying horizontal between the two long sills, turns in boxes bolted on the cross sills which are tenoned into the long sills, on the other end of said shaft, is another cast iron wheel twenty-two inches in diameter with seven gearing two & a quarter inches wide which meshes into a three inch pinion on a shaft of wrought iron an inch & a quarter square sixteen inches long with two bearings of two inches each eight inches apart the end of the shaft projecting four inches beyond the bearing to receive a band wheel two feet four inches in diameter -

The band wheel is made with wooden arms three inches square locked across each other & filled three inches wide for the band to run on - The shaft runs in boxes like those of the cylinder in the thrashing machine & is supported by framing two posts nine inches wide & two inches thick into the large sills, & two girts locked into the posts & secured by iron bolts passing thro' the whole together -

The horizontal shaft has a bridge over it confined on the long sills for the horses to pass over on - The long sills for convenience should be sunk to a level with the surface of the ground - The same motion may be given to the machinery by using a coverage wheel instead of the crown wheel - The wheels in the gearing may be enlarged or diminished to such sizes as may be necessary -

I claim as my invention or improvement in the above described horse power the construction of the frame & the application of the gearing in
